UNITED STATES PATENT OFFICE

COLUMBUS MONROE GIDLEY, OF CORSICANA, TEXAS

ELEVATOR

Application filed April 7, 1928. Serial No. 268,231.

This invention relates to elevators and more particularly to elevators of the type employed in conjunction with oil well drilling apparatus for hoisting drill pipe and the like within the derrick.

In oil well drilling, it is necessary to periodically withdraw the drill pipe from the well and whenever this becomes necessary, the pipe is removed in lengths each including 10 a certain number of sections connected by their couplings. The elevators employed for this purpose ordinarily comprise hingedly connected jaws which are clamped about the pipe beneath one of these couplings, so that 15 the section may be raised or lowered as required. In such ordinary structures, assuming the elevator to have been clamped about the pipe to elevate the same and a predetermined number of sections to have been withdrawn, 20 drawn from the well in order to release the elevator, it is necessary that an attendant be positioned at a point adjacent the top of the well to accomplish the uncoupling function. After the sections have been withdrawn as 25 hereinbefore stated, they are seated at their lower ends upon the derrick floor or upon a rack carried thereby and accordingly when it is desired to pick up one of these sections to couple it to the well string for lowering 30 and to lower the coupled unit with this string, it is necessary that the attendant occupy the same position and connect the elevator to the pipe at its upper end and immediately beneath the uppermost coupling.

It will be obvious that this attendant occupies a perilous position and that furthermore his services are not available upon the derrick floor where during such operations they are necessary. Accordingly, an important object 40 of the present invention is to provide an elevator which, when coupled to a pipe at the upper end thereof, may be lowered to the lower end of the pipe for uncoupling without the necessity of disengaging it from the 45 pipe and which, when it is to be engaged with a pipe adjacent the upper end thereof, which pipe has a predetermined number of couplings thereon, may be engaged with this pipe at the lower end thereof and borne upwardly over the pipe without grasping the

same until the last coupling is reached when gripping jaws carried by the elevator become effective to engage the pipe.

A further object of the invention is to provide in a device of this character a structure 55 which is readily manipulatable, which may be readily assembled and which will be durable and efficient in service.

These and other objects I attain by the construction shown in the accompanying drawings, wherein for the purpose of illustration is shown a preferred embodiment of my invention and wherein:

Figure 1 is a plan view partially in section of an elevator constructed in accordance with 65 my invention;

Figure 2 is a section on the line 2—2 of Figure 1;

Figure 3 is a detail view showing the connections employed for operation of the second jaw;

Figure 4 is a detail sectional view showing the manner of adapting the jaws for use with drill pipe of different sizes.

Referring now more particularly to the 75 drawings, the elevator comprises a frame formed in two sections 10 and 11, pivotally connected at one side, as indicated at 12, and provided at the opposite side with a spring-pressed latching mechanism 13 whereby the 80 sections may be held in assembled relation about a pipe. Each section has means for connecting a bail thereto, as indicated at 13^a, and is provided adjacent the free end thereof with a hand hold 14 whereby the sections 85 may be swung about their pivot. Each section is further provided adjacent its lower end with a shelf or ledge 15 provided with a groove having a curved bottom, as indicated at 16, receiving a curved rib 17 upon 90 the lower end of a jaw 18, so that these jaws are pivotally mounted at their lower ends to permit the upper ends thereof to be swung inwardly to engage a pipe P.

The section 10 has formed therein a recess 95 19 opening through the top and inner face thereof and at the sides of this recess has extending upwardly therefrom ribs 20 produced upon the upper face of the section.

The outer wall of the recess has a threaded 100

bore 21 within which is seated a removable plug 22 having at its inner face an axial projection 23. This axial projection mounts a spring 24 and extends into a cavity formed in the rear end of a plunger 25 against which the opposite end of the spring seats. This plunger is pivotally connected to the rear face of the associated jaw 18 adjacent the upper end thereof, as indicated at 26, with the result that the spring 24 constantly tends to urge this jaw inwardly. Seated in the recess and held in position therein by a cap 27 is an assembly comprising a pair of spaced plates 28. Between these plates adjacent the upper end thereof is pivoted a trigger 29 having pivoted thereto a spring-pressed arm 30, the spring 31 of which constantly urges the arm and accordingly the lower end of the trigger 29 outwardly. The inner end of this trigger has pivoted thereto a dog 32 accessible from the outer face of the section 10 by elevating a panel 33 pivoted to the cap 27 as at 34. This dog has an undercut notch 35 formed in the upper edge thereof which, when the trigger 29 is withdrawn within the confines of the section 10, may be hooked over a pin 36 carried by the plate assembly to hold the trigger in its retracted position.

For convenience in engaging this dog to withdraw the trigger against the action of the spring 31, the dog has projecting from opposite sides thereof studs 37 with which a hooked tool may be engaged. Slidable between the plates is an actuating bar 38 having at its lower face a hook 39, the purpose of which will presently appear. This bar is frictionally held in position by a spring 39^a and has in its upper surface ratchet teeth 40 for coaction with the dog 37, so that when the trigger 29 is forced inwardly, the bar 38 is advanced one step outwardly.

The section 10 is provided with a bore in which is mounted a shaft 41, this shaft having its inner end extending into the cavity and between the plates 28 where it has secured thereto a latch dog 42 adapted to engage a latching shoulder 43 formed on the plunger 25 to hold the plunger in retracted position with the jaw 18 in such position that it may not engage with a tool joint J upon a pipe which is passing between these sections. This dog has a tail 44 which is arranged in the path of movement of the hook 39 of the bar 38.

It will be obvious that if the trigger 29 is forced inwardly a predetermined number of times, the bar 38 will be advanced sufficiently to bring the hook 39 into engagement with the tail 44, shifting the dog 42 to release the plunger, so that the jaw 18 may be shifted thereby to a position where it will extend into the path of the joint J as it passes between the sections. It will also be obvious that at this time, the shaft 41 will

65 be oscillated.

The outer end of the shaft 41 has secured thereto an arm 45, to the outer end of which a connecting rod 46 is connected. The wing 47 of the section 10 at the latching side of the elevator has a bore opening through the end face thereof, which is indicated at 48 and in this bore is arranged a trip bar 49 to which the end of the connecting rod 46 is connected. A spring 50 constantly urges the trip bar outwardly and normally maintains the shaft 41 in such position that the dog 42 will engage with the plunger. The jaw 18 of the section 11 has upon one wing thereof an outstanding lug 51 which, when the sections are in closed position, is in the path of the trip bar 49 and is normally held thereby in a position such that it is held out of the path of the joints J of the pipe P passing through the elevator.

When, however, the dog 42 is operated by the hook 39 of the bar 38, the resilient oscillation of the shaft 41 causes the trip bar to be withdrawn so that the jaw of the section 11 may move inwardly and be positioned to engage the pipe joint J. The jaws 18 are preferably so constructed that they may have applied thereto bushings 52 to adapt these jaws for use with pipe of different sizes. These bushings are at present disclosed as having shoulders 53 to overhang the upper ends of the jaws and being held in position by bolts 54 extending through these portions and into the upper ends of the jaws.

In the use of the device, in withdrawing tubing or drill pipe from the well, the trigger is withdrawn to its inoperative position and secured thereby hooking the dog 32 upon the pin 36. The dog 42 is tripped to release the plunger so that the jaws 18 are normally urged inwardly. The sections of the elevator are then clamped together about the upper end of the drill pipe immediately below the collar secured thereto and which is projecting above the upper end of the well. The hoisting apparatus is then brought into play to lift the string until the desired extension thereof is obtained, when the well string is supported by the usual slips (not herein shown) during the uncoupling operation. When the pipe is uncoupled, the lower end thereof is moved to the storage position and sufficient slack is given the cable lines to enable the upper end of the pipe to assume its proper position. The cable may, after the pipe is properly positioned, be slackened away, allowing the elevator to pass downwardly over the pipe and the jaws 18 will simply ratchet over the joints until the elevator reaches the lower end thereof when a workman upon the floor of the derrick may release the elevator to enable it to be swung to the center of the derrick to re-engage the drill pipe.

In returning the sections, as has been hereinbefore pointed out, the elevator is first used

to lift the sections of pipe and support them while they are being engaged with the drill pipe or in the hole and then as a means for supporting the assembled pipe while it is lowered into the hole. During this operation, the trigger 29 is released and the jaws are locked in their retracted position by the dog 42. The elevator is clamped about the lower end of the pipe which is seated upon the rack or floor of the derrick and power applied to lift the elevator. The elevator moves upwardly along this pipe and the trigger 29 is forced inwardly as it passes each tool joint.

15 With the construction at present illustrated, as the third tool joint is passed, the dog 42 is released, releasing the plunger and oscillating the shaft 41, so that both jaws 18 are positioned to engage the next tool joint 20 and lift the pipe. It will be obvious that when the assembled pipe has been lowered, the elevator is again at the floor level, so that it may be handled therefrom and after it has been reset need merely be swung transversely 25 of the derrick to engage a second pipe section.

Since the construction hereinbefore set forth is capable of a certain range of change and modification without materially departing from the spirit of the invention, I do not limit myself to such specific structures except as hereinafter claimed.

I claim:—

1. In an elevator for handling pipe sections having spaced projecting portions, a collar having means to engage beneath one of the projections, a member holding said means in inoperative position to thereby permit the collar to be moved upwardly over the pipe and releasing apparatus for said member carried by the collar and positioned to engage said projections, said releasing means being rendered operative by engagement therewith of a predetermined number 45 of projections.

2. In an elevator for handling pipe sections having spaced projecting portions, a collar to surround the pipe having a jaw normally positioned to engage beneath one of said portions, means for holding the jaw in retracted position to permit passage of the projecting portions of the pipe section, and means actuated by the passage of a predetermined number of said portions through 55 said collar releasing said holding means.

3. In an elevator for handling pipe sections having spaced projecting portions, a collar to surround the pipe having a jaw normally positioned to engage beneath one of said portions, means for holding the jaw in retracted position to permit passage of the projecting portions of the pipe section, a pipe engaging trigger pivoted to said collar and shifted by each of said portions as it passes, 65 and means actuated by said trigger after a

predetermined number of operations thereof releasing said holding means.

4. In an elevator for handling pipe sections having spaced projecting portions, a collar to surround the pipe having a jaw normally positioned to engage beneath one of said portions, means for holding the jaw in retracted position to permit passage of the projecting portions of the pipe section, a pipe engaging trigger pivoted to said collar and shifted by each of said portions as it passes, 70 and a member advanced one step by the trigger each time that the trigger is shifted, said member coacting with said holding means to release the same after the member has been advanced a predetermined 75 number of steps.

5. In an elevator for handling pipe sections having spaced projecting portions, a collar to surround the pipe having a pair of opposed jaws normally positioned to engage beneath one of said portions when the collar is moved upwardly over the pipe, a latch holding one of said jaws in retracted position, means operatively connected with the latch and holding the other of the jaws in retracted position when the latch is in latching 80 position, and means actuated by the passage of a predetermined number of said portions through said collar for releasing said 85 holding means.

6. In an elevator for handling pipe sections having spaced projecting portions, a collar to surround the pipe having a pair of opposed jaws normally positioned to engage beneath one of said portions when the collar is moved upwardly over the pipe, a latch holding one of said jaws in retracted position, means operatively connected with the latch and holding the other of the jaws in retracted position when the latch is in latching 90 position, and means actuated by the passage of a predetermined number of said portions through said collar for releasing said 95 holding means, said jaws retracting during movement of said portions through the collar in the opposite direction to permit passage of the portions.

7. In an elevator for handling pipe sections having spaced projecting portions, a collar to surround the pipe having a pair of opposed jaws normally positioned to engage beneath one of said portions when the collar is moved upwardly over the pipe, a latch holding one of said jaws in retracted position, means operatively connected with the latch and holding the other of the jaws in retracted position when the latch is in latching position, a pipe engaging trigger pivoted to said collar and shifted by each of said portions as it passes, 100 and means actuated by said trigger after a predetermined number of operations thereof releasing said holding means.

8. In an elevator for handling pipe sections having spaced projecting portions, a 105

collar to surround the pipe having a pair of opposed jaws normally positioned to engage beneath one of said portions when the collar is moved upwardly over the pipe, a latch holding one of said jaws in retracted position, 5 means operatively connected with the latch and holding the other of the jaws in retracted position when the latch is in latching position, a pipe engaging trigger pivoted to said collar and shifted by each of said 10 portions as it passes, and a member advanced one step by the trigger each time that the trigger is shifted, said member coacting with said holding means to release the same after the member has been advanced a predetermined number of steps.

9. In an elevator for handling pipe sections having spaced projecting portions, a collar to surround the pipe, a jaw pivoted thereto 20 and movable to a position where it will engage beneath a projecting portion to support the pipe within the collar, a spring-pressed plunger connected to the jaw and urging the jaw to said position, a latch carried by the collar and engaging the plunger to hold 25 the jaw in retracted position, and means carried by the collar and positioned for engagement by said projecting portions during their passage therethrough operating after engagement therewith of a predetermined number of 30 said projections to release the latch.

10. In an elevator for handling pipe sections having spaced projecting portions, a collar to surround the pipe, a jaw pivoted thereto 35 and movable to a position where it will engage beneath a projecting portion to support the pipe within the collar, a spring-pressed plunger connected to the jaw and urging the jaw to said position, a latch carried by the collar and engaging the plunger to hold 40 the jaw in retracted position, the latch having a tail, a longitudinally shiftable bar having a member to engage the tail when the bar has been advanced to a predetermined 45 extent and release the latch, the member carried by the collar and positioned to be engaged by said projections during their passage through the collar, said member at each engagement therewith of a projection advancing said bar.

11. In an elevator for handling pipe sections having spaced projecting portions, a collar to surround the pipe, a jaw pivoted thereto and movable to a position where it will 55 engage beneath a projecting portion to support the pipe within the collar, a spring-pressed plunger connected to the jaw and urging the jaw to said position, a latch carried by the collar and engaging the plunger to hold 60 the jaw in retracted position, means carried by the collar and positioned for engagement by said projecting portions during their passage therethrough operating after engagement therewith of a predetermined number of said 65 projections to release the latch, a second jaw

carried by the collar and opposed to the first named jaw and adapted to normally assume a position where it will engage beneath said projections, and means withdrawn by withdrawal of the latch normally maintaining the last named jaw in retracted position.

12. In an elevator for handling pipe sections having spaced projecting portions, a collar to surround the pipe, a jaw pivoted thereto and movable to a position where it will engage beneath a projecting portion to support the pipe within the collar, a spring-pressed plunger connected to the jaw and urging the jaw to said position, a latch carried by the collar and engaging the plunger to hold the jaw in retracted position, means carried by the collar and positioned for engagement by said projecting portions during their passage therethrough operating after engagement therewith of a predetermined number of said projections to release the latch, a second jaw carried by the collar and opposed to the first named jaw and adapted to normally assume a position where it will engage beneath said projections, a spring-pressed element retaining the last named jaw in retracted position, and a connection between the spring-pressed element and the latch whereby said element is withdrawn simultaneously with the latch.

13. In an elevator for handling pipe sections having spaced projecting portions, a collar formed in hinged sections and having means whereby it may be secured in closed position about the pipe, said collar being passable over the pipe section and its projecting portions from end to end of the pipe after assembly thereabout, jaws carried by said collar to engage and support pipe, means urging said jaws into engagement with the pipe, means retaining the jaws in retracted position to thereby permit the collar to be moved from one end to the other of the pipe, and means automatically releasing said retaining means when the collar has reached a predetermined position upon the pipe.

14. In an elevator for handling pipe sections having spaced projecting portions, a collar formed in hinged sections and having means whereby it may be secured in closed position about the pipe, said collar being passable over the pipe section and its projecting portions from end to end of the pipe after assembly thereabout, jaws carried by said collar to engage and support pipe, means urging said jaws into engagement with the pipe, means retaining the jaws in retracted position to thereby permit the collar to be moved from one end to the other of the pipe, and means automatically releasing said retaining means when the collar has passed a predetermined number of said projections in its movement from one end of the pipe to the other thereof.

15. In an elevator for handling pipe sec-
